ROLLER BORING DRILL

Robert W. Schlumpf and Ralph P. Sherman,
Houston, Tex., assignors to Hughes Tool Com-
pany, Houston, Tex., a corporation of Texas

Application March 9, 1935, Serial No. 10,257

2 Claims. (Cl. 255—71)

Our invention relates to roller boring drills such as are employed in drilling deep wells for oil, gas, sulphur and the like.

The improvement consists in the provision of 5 an effective type of bearing for the rolling cutters.

The invention is particularly applicable to cutters upon the so-called cone cutters employed in hard formation bits.

10 It is an object of the invention to provide a bearing surface upon the cutter shaft which may have a rotation with the cutter upon the shaft but at a slower rate of rotation than that of the cutter itself, thus allowing a smooth rotation of 15 the cutter and a prolonged life upon the bearing.

We desire to provide a form of anti-friction bearing which will be of strong and sturdy construction and not liable to become broken in use. We wish to avoid the difficulty commonly experienced with roller bearings where said bearings will be broken and moved out of position 20 during the operation of the cutter.

In the drawing, Fig. 1 is a side view partly in elevation and partly in central vertical section 25 showing one embodiment of the invention.

Fig. 2 is a broken sectional detail showing a cutter upon its shaft with a slightly different form of bearing.

Fig. 3 is a view similar to Fig. 2 but illustrating 30 a still different embodiment of the invention.

Figs. 4 and 5 are perspective views of the bearing members removed from their position upon the shaft.

We have illustrated the invention as applied 35 to the usual type of so-called cone bit. Said bit has a head 1 with an upwardly tapered and threaded shank 2 for attachment to a drill collar. Said head has two downwardly diverging legs 3, the inner faces of which are inclined upwardly 40 and inwardly and have an integral shaft 4 thereon. Said shaft projects downwardly and inwardly at approximately right angles to the plane inner face of the leg upon which it is formed.

The head has a longitudinal passage 5 there- 45 through to conduct flushing fluid to the cutters in the usual manner.

The shafts 4 are shown as having an upper cylindrical area 6 of strong construction and a forward projection 7 thereon of smaller diameter. 50 The general form of the shaft is therefore a tapered one conforming to the general contour of the conical shaped cutter 8 which is mounted thereon.

The cutter 8 is toothed in the usual manner and has its inner bearing surface shaped to con- 55 form to the shape of the shaft 2.

The bearings between the cutter and the shaft which form the subject matter of our invention include a row of balls 9 fitting within the raceway partly within the shaft and partly within the inner wall of the cutter shell. These balls are introduced into the raceway when the cutter is mounted upon the shaft through a transverse opening in the head. Said opening is closed thereafter by a plug 10 held in place by a bond of welding material 11. Toward the forward end 5 of the cutter shaft we employ a thin sleeve 12 of bearing metal separating the cutter from the shaft and conforming in shape to the outer surface of the shaft. Its inner end is of enlarged 10 diameter, fitting over the body 4 of the shaft and the forward end is reduced to engage closely but rotatably upon the projection 7. This bearing member forms a sleeve or thimble which is rotatable upon the shaft and also relative to the cutter. The bearing sleeve may be made of any 15 desired metal resistant to wear such as carburized steel and it is intended to increase the life of the cutter and the shaft during the operation of the bit.

It is contemplated that when the bit is operated 20 the cutters will roll on the bottom of the hole, thus rotating upon the cutter shaft. The bearings 9 will take up the thrust of the cutter at the outer end thereof. The bearing sleeve 12 will rotate partly with the cutter and there will 25 be relative movement between the cutter and the bearing sleeve and also between the bearing sleeve and the shaft. There will thus be less 30 wear upon the cutter and the sleeve will be of sufficiently strong and sturdy construction that 35 it will not break up in use.

The common difficulty with cutters of this kind, that bearings introduced between the forward end of the cutter and the shaft will crack up and interfere with the operation of the cutter, will be 40 largely eliminated.

In Fig. 2 the structure is approximately the same as in Fig. 1 with the exception of the bearing sleeve. In this particular embodiment we 45 provide two separate rings or sleeves 13 and 14 between the interior of the cutter shell and the outer surface of the shaft. The sleeve 13 is set within a recess in the shaft and is supported upon the forward end of the large portion of the shaft. 50 The ring 14 is fitted over the projection 7 upon the shaft and is of materially smaller diameter. The two bearings are both of them rotatable upon the shaft and in use will wear on both their outer and inner surfaces, thus allowing a freer 55

rotation of the cutter but also serving to form a substantial support not liable to break in use.

In Fig. 3 is a still different embodiment. The shaft 4' has an annular recess 15 adjacent the base of the shaft to receive a row of rollers 16 to support the cutter at that point. The retaining row of balls 17 is placed forwardly on the shaft from the roller raceway, these balls being inserted through an opening closed by the plug 10', as previously described. The forward reduced end 7" upon the shaft has an annular recess 18 to receive a bearing ring 19. Said ring is divided longitudinally, as shown in Fig. 5, so that it may be fitted over the end of the shaft and within the groove 18.

The operation of this bearing is similar to those previously described, the rollers and balls serving in the usual manner to provide an anti-friction bearing for the shaft along its larger diameter. On the smaller diameter of the projection 7" the ring 19 operates to provide a reduced friction at that point being rotatable partly with the cutter upon its seat within the recess 18. The ring is thus able to reduce friction at the forward portion of the shaft and still be of such construction that it will not break up under the extreme pressures to which it is subjected in use.

In Fig. 4 we have shown how the bearing sleeve 30 may if desired be formed with perforations 20 to receive lubricating material. It is customary in the mounting of the cutter upon the shaft to thoroughly cover the bearings with a heavy lubricant. The provision of the openings in the bearing sleeves provides still further space into which

the lubricant may be received and decrease the friction of operation to some extent. It is to be noted that the cutter is spaced slightly from the shaft except where it rests upon the bearings to thus permit the circulation of water from the hole around the bearings and keep them cooled during operation. It will be seen that our form of bearing is such that it can not be easily broken even where submitted to heavy pressures. The usual difficulty of having the bearings toward the forward end of the shaft broken under the heavy strains encountered will be overcome to a large extent and the life of the bearing materially prolonged.

What we claim as new is:

1. A drill head, a forwardly inclined cutter shaft thereon, a cutter enclosing the end of said shaft, anti-friction bearings for said shaft acting also to retain said cutter on said shaft, a reduced forward extension on said shaft, an annular raceway recessed in said extension and a longitudinally divided ring of bearing material in said raceway, the end walls of said recess limiting longitudinal movement of said ring.

2. A well drill head, a cutter shaft thereon, a reduced extension on said shaft, a cylindrical recess on said extension, a cutter enclosing the end of said shaft and extension, means to retain said cutter on said shaft, and a bearing ring on said extension fitting behind a shoulder of said recess thereon, and rotatable relative to said shaft and said cutter.
